UNITED STATES PATENT OFFICE.

JAMES B. ANDERSON, OF PITTSBURGH, PENNSYLVANIA, ASSIGNOR TO PUMPLESS BLOW TORCH COMPANY, OF PITTSBURGH, PENNSYLVANIA.

PLUMBER'S FURNACE.

Application filed September 28, 1921. Serial No. 503,963.

To all whom it may concern:

Be it known that I, JAMES B. ANDERSON, a citizen of the United States of America, residing at Pittsburgh, in the county of Allegheny and State of Pennsylvania, have invented certain new and useful Improvements in Plumbers' Furnaces, of which the following is a specification.

This invention refers to plumbers' furnaces, and more particularly to such furnaces operated with liquefied gas as fuel.

One of the principal objects of my invention is to provide a furnace which can be adjusted to accommodate melting-pots of various diameters. A further object is to provide a furnace that is adapted for the rapid heating of soldering-irons as well as for heating solder in melting-pots, or other material contained in vessels. Still another object is to provide a furnace that can be operated without requiring a pressure pump as now commonly used on such devices. Further objects will appear from the drawings and specification which form a part of this application.

In the present application I desire especially to describe my new furnace as applied to a new type of torch-burners illustrated and claimed in a co-pending application for 30 patents of even date, as well as to blow torches described in the following patents: No. 1,364,972, June 11, 1921, and Nos. 1,390,264 and 1,390,265 dated Sept. 13, 1921, which were issued to Charles H. Allen and myself.

Referring to the drawings:

Fig. 1 is a front elevation, partly shown in section, of my plumber's-furnace.

Fig. 2 is a top plan view corresponding 40 to Fig. 1.

Fig. 3 is a fragmentary side elevation of my furnace.

The preferred construction of my furnace comprises a fuel tank 1, shown pumpless 45 because of the use of liquefied gas as fuel, as explained in the aforementioned patent references. Centrally of the top of the tank is mounted the vertical burner-device 2 provided with the test-valve 3, the safety-valve 4, the liquid valve 5 and the gaseous fuel valve 6. The burner proper 7 is of the non-clogging type described in the co-pending application of even date, and is surrounded by the perforated flame-tube 8. The pilot-burner illustrated in said application is

eliminated owing to the fact that the vertical arrangement of the burner-device would so diminish the efficiency of vaporization of the fuel from the main burner as to not warrant the additional expenditure which said 60 pilot-burner would occasion.

The upper structure of the furnace consists of the posts 9, securely mounted on the tank and threaded at the top. These posts support the heating-chamber 10 which is mounted thereon by means of the apertured ears 11 formed integral with the body of the heating-chamber and which are secured between the clamping nuts 12 and 13, 70 threaded on said posts.

The heating-chamber is open at the top, while in the bottom thereof I provide the oblong flame-aperture 15 which is of sufficient length to accommodate several soldering-irons at a time. The flame-aperture is 75 also surrounded by the required number of smaller circular apertures for the purpose of insuring a proper upward draft of air within the heating-chamber.

The soldering-irons are introduced into 80 the heating-chamber through the rectangular opening 17, laterally disposed on the heating-chamber. This opening is provided with a cover 18, hinged at the lower side by the pin connections 19. As will be noted 85 in the drawings, the opening is surrounded by a rim 20, having an inclined face, so that the cover (once shut) will retain its closed position by its own weight. Centrally of the lower side of the cover I provide the extension 21 for the purpose of limiting the opening of the cover to the horizontal position shown in dot and dash lines in Fig. 3, thus securing a substantially 90 level support for the solder-irons.

Intermediate the ears 11 and the top nuts 12 are mounted the flat and oblong links 22 which act as support for the melting-pots. These links can be adjusted longitudinally to accommodate various sizes of melting-pots. 100 Suitable notches 23 are cut radially in the upper edge of the heating-chamber to act as lateral guides for said links. The depth of the notches is preferably made such that the links will not protrude above the edge of 105 the heating chamber.

When the furnace is to be used for heating soldering-irons exclusively, it is advisable to cover the top of the heating chamber in order to increase the utilization of the 110

flame. For this purpose I provide the heating-chamber with the removable top lid 24, of somewhat smaller diameter than the inside of the heating-chamber. This lid is furnished with an adequate number of lugs 25 having downwardly bent extensions 26 which embrace the outer periphery of the heating-chamber, to properly maintain the lid thereon. When operating the furnace 10 with the lid on, the gases of combustion will escape through the annular space 27 provided between the lid and the wall of the heating-chamber.

Diametrically disposed on the heating-chamber, and securely mounted thereon, are 15 the two eyes 28 which are engaged by the handle or bail 29, by means of which the furnace is carried about.

From the foregoing description, taken in 20 connection with the accompanying drawings, it should be apparent that I provide a plumber's-furnace of practical and substantial construction. It is of course understood that the parts may be constructed in 25 various manners than shown and I desire not to be limited in any manner, except as set forth in the claims hereunto appended.

What I claim is:

1. In a plumber's-furnace, the combination 30 of a heating-chamber open at the top; a plu-

rality of radially adjustable supports for vessels positioned upon said heating-chamber; a removable lid for, and of lesser diameter than, said heating-chamber, and means for supporting said lid thereon. 35

2. In a plumber's-furnace, the combination of a heating-chamber open at the top; a plurality of radially adjustable supports for vessels positioned upon said heating-chamber; a removable lid for, and of lesser diameter than, said heating-chamber, and a plurality of lugs extending outwardly of said lid and having downwardly bent extremities 40 for peripheral engagement with said heating-chamber. 45

3. In a plumber's-furnace, the combination of a fuel tank; a plurality of vertical posts mounted thereon and threaded at their upper ends; a heating-chamber supported by said posts; a plurality of apertured ears secured on said heating-chamber and engaged by said posts; a plurality of oblong links positioned on said ears and engaged by said posts; a plurality of notches provided in the upper edge of said heating-chamber for radially guiding said links, and threaded nuts 50 engaging said posts for securing said links 55 in their selected position.

In testimony whereof I affix my signature.

JAMES B. ANDERSON.
